A.C.Power,

UNITED STATES PATENT OFFICE.

ALEXANDER C. POWER, OF PENDLETON, OREGON.

SWITCH-BOX.

1,141,359.

Specification of Letters Patent.

Patented June 1, 1915.

Application filed September 19, 1910. Serial No. 582,654.

To all whom it may concern:

Be it known that I, ALEXANDER C. POWER, a citizen of the United States, residing at Pendleton, in the county of Umatilla and 5 State of Oregon, have invented certain new and useful Improvements in Switch-Boxes, of which the following is a specification, reference being had to the accompanying drawings.

10 This invention relates to an improved switch box and has for its primary object to provide an improved box construction for housing the switch mechanism, and means for mounting the same in the wall of a 15 building.

15 The invention has for another and more specific object to provide a switch box including a body, and a face plate to close one end of said body, in combination with an 20 inner insulating casing for the switch mechanism adapted to be arranged within said box and immovably held in position by said face plate, without necessitating the employment of other securing means such as bolts, screws, 25 or the like.

25 The invention consists in the construction, combination and arrangement of devices hereinafter described and claimed.

In the accompanying drawings,—Figure 30 1 is a side elevation of an electric switch box constructed in accordance with my invention, showing the same in a wall, the latter being indicated in section. Fig. 2 is a vertical sectional view of my improved switch 35 box. Fig. 3 is a horizontal sectional view of the same on a plane indicated by the line a—a of Fig. 2. Fig. 4 is a detail front elevation of the porcelain inner case, and Fig. 40 5 is a similar view of the wall plate. Fig. 6 is a detail plan of one of the binding posts 10.

45 In disclosing the manner in which my improved switch box is intended to be used, I have illustrated in the accompanying drawings a switch mechanism which is mounted within an insulating inner case 1 which is preferably made of porcelain, but may be made of any other suitable non-conducting material. The said inner case is rectangular 50 in form and is open at its front side. The bottom or inner side 3 of the inner case is thicker than the side walls 4. The case may be of any suitable length according to the 55 number of switches which are to be disposed therein. Where more than one switch is employed in the case, the latter is pro-

vided with a number of cells corresponding in number with the switches, there being one cell for each switch, the cells being here indicated at 5 and separated from one another 60 by thin partition walls 6, with which the porcelain inner case is formed. The rear side or base of the inner case is also provided for each cell thereof with a pair of openings 7 for the reception of the threaded stems 65 8 of the binding posts 9, 10, and also with diametrically enlarged counter-sinks 11 for the reception of the nuts 12 and washers 13 on the said threaded stems of the binding posts, the shoulders 14 of the binding posts 70 bearing against the inner side of said base or rear wall. Said base or rear wall of the inner case is also provided for each cell thereof with openings 15 through which wires may be run to the binding posts. The 75 upper and lower sides of the inner case are also provided for each cell thereof with openings 16 through which a screw driver may be run to tighten the screws against the wires in the binding posts. The said 80 inner case is provided on its rear or inner side with studs 17 which project from its corners. Each binding post 9 has its inner end bifurcated to provide a pair of parallel spaced lugs 18. Each binding post 10 has a 85 pair of parallel spaced switch plates, the said plates being held in place by a pin 21 which passes through transversely aligned openings with which said plates and said binding posts are provided.

90 A switch knife 22 is provided with an integral arm 23 which projects at right angles therefrom. The inner end of the switch knife is pivotally mounted between the lugs 18 of the binding post 9 and on a 95 pivot screw 24. A handle 25 is secured to the outer end of the switch knife, said handle being connected by a screw 26 to a sleeve 27, which sleeve has a bifurcation which receives the outer end of the switch knife and is attached to the switch knife by a pin 28 as shown. On opposite sides of the arm of the switch knife, near the inner end of the said arm, are a pair of cleat bars 29 which are secured by a screw 30. A switch blade 31 which is preferably made of sheet copper or other metal of high conductivity has its inner portion disposed between the projecting ends of the cleat bars and pivotally secured thereto by a screw 32, the extreme inner end of the said switch blade being beveled on the side next to the arm 23 as

at 33 so that the said switch blade is adapted for slight angular movement with respect to the arm 23. Coil springs 34 are disposed on opposite sides of the arm 23, and the 5 switch blade, and have their ends connected respectively to said arm and said switch blade, the function of the said springs being to make a quick break of an opening movement of the switch blade. By moving the 10 switch knife, by means of its handle 25, the switch blade and a portion of the arm 23 may be caused to enter the space between the plates 19 of the binding post 10, and hence establish electrical connection between 15 the post 9 and the post 10, or moved outwardly from between said arms so as to break said connection.

It will be understood that the switch mechanism above described constitutes no 20 part of the present invention, and various other switch constructions may be utilized in connection with my improved box or housing. An inner insulating casing of the construction above described will, however, 25 be employed in every instance. The outer case or switch box proper will now be described in detail. While opening the switch knife, the switch blade will lag, and remain in contact with the plates 19 of the binding 30 post 10, until after the arm is free from said plates, and then the tension on the springs will become so great as to cause them to quickly withdraw the switch blade from between the said plates and close the same 35 against the arm of the switch knife, thereby making a quick break of the circuit and avoid injurious sparking.

The inner case 1 of insulating material is 40 inclosed in a metallic outer case 34. The side walls 35 and rear wall 36 of the said outer case are integral, the said side and rear walls being formed from a rectangular sheet of metal bent to dispose the side walls 35 parallel with each other. The rear wall 45 36 is provided, for each cell of the inner casing, with a pair of openings 37 which afford access to the openings 15 of the inner casing, and are concentric therewith. On the side walls 35 of the outer case at the 50 front edges thereof are angle pieces 38, the inner arms of which bear against the side walls 35 and are adjustably secured thereto by screws 39. The outer arms of the said angle pieces are flush with the front sides 55 of the inner and outer casings. The top 40 and bottom 41 of the outer casing are made of sheet metal, are identical in construction, and each of them is formed with side flanges 42 to bear against the side walls 35, and inner flanges 43 to bear against the rear wall 36, the said flanges being secured to the said walls by means of screws 44 which admit of the said top and bottom plates being 60 readily attached to or detached from the side walls and rear side of the outer casing.

The said top and bottom plates of the outer casing are provided with openings 45 which are coincident with the top and bottom openings 16 of the inner casing, and the said top and bottom plates of the outer casing are 70 provided with angle pieces 46 which are identical in construction with the angle pieces 38, are secured by screws 47, and the front arms thereof are disposed flush with the front sides of said inner and outer casings. The front, open sides of the inner and outer casings are covered by a face plate 48, the length and breadth of which are such as to enable the same to entirely cover the inner and outer casings, and to also 80 cover the angle pieces 38, 46 which project from the sides and top and bottom of the outer casing. The angle pieces 38 which are on the sides of the outer casing are secured to the wall *a* by means of suitable 85 screws. The face plate is secured to the angle pieces 46 which project from the upper and lower sides of the outer casings by means of screws 49 which are inserted in openings with which said face plate and said angle pieces are provided. 90

The face plate is provided near its lower portion with vertical slots 50 corresponding in number with the cells and switches, there being one of the slots 50 provided for each switch knife. the inner narrowed portion of the handle of the switch knife operating in the said slot, the major portion of the handle projecting outwardly from the face plate 100 as shown in Fig. 1.

In order to open any one of the switches, it is only necessary to draw downwardly on the handle of the switch knife. To close 105 said switch, said handle must be moved upwardly in the slot 50. The studs 17 on the rear side of the inner casing bear against the corners of the rear wall of the outer casing, and serve to space said rear wall of the outer casing from that of the inner casing 110 as shown.

By providing the inner casing with an appropriate number of cells, and correspondingly regulating the size of the outer casing, my invention may be employed for any number of switches as will be understood. 115

I claim:—

1. The herein described switch box including an outer rectangular casing open upon its front side, the casing body consisting of top and bottom walls and integral side and rear walls detachably secured to said top and bottom walls, an insulating casing disposed within the outer casing but entirely disconnected therefrom, said inner and outer casings having openings in their top and bottom walls, said inner casing being provided with lugs projecting from its rear face for engagement with the rear wall of the outer casing whereby the openings of the insulating casing are disposed in coinciding 120 125 130

relationship with the openings of the outer casing, said inner casing also having its front side open and the front edges of the walls of said casing being disposed in the 5 same plane, as the front edges of the walls of the outer casing, and a face plate removably attached to the outer casing and extending over the open sides of the inner and outer casings and intimately engaged 10 with the front edges of the walls of said casings.

2. The herein described switch box comprising an outer casing of rectangular form in cross section having openings in its top 15 and bottom walls and adjacent to the rear end thereof, an insulating inner casing disposed within said outer casing and having an integral rear wall provided with spacing lugs to engage the rear wall of the outer casing, said inner casing also being provided 20

in its top and bottom walls with openings to register with the openings in the corresponding walls of the outer casing when said lugs engage with the rear wall of the outer casing, the front sides of said inner and outer casings being open and the forward edges of the walls of said casings being disposed in the same plane, and a face plate removably secured to the top and bottom walls of the outer casing and 25 engaging with the forward edges of the walls of both of said casings to prevent longitudinal movement of the inner casing with respect to the outer casing.

In testimony whereof I hereunto affix my 30 signature in the presence of two witnesses.

ALEXANDER C. POWER.
